(57) **CLAIM**

I claim the ornamental design for a pet carrier, as shown and described.

DESCRIPTION

The application file contains at least one drawing executed in color. Copies of this patent application with color drawings will be provided by the Office upon request and payment of the necessary fee.

FIG. 1 shows a front view of the pet carrier showing my new design, without the shoulder strap, according to the first embodiment;

FIG. 2 shows a rear view thereof;

FIG. 3 shows a left side view thereof;

FIG. 4 shows a right side view thereof;

FIG. 5 shows a top view thereof;

FIG. 6 shows a bottom view thereof;

FIG. 7 shows a perspective view thereof;

FIG. 8 shows a perspective view thereof, with handles down, and with the shoulder strap attached in an extended position.

FIG. 9 shows a front view of a pet carrier showing my new design, without the shoulder strap, according to a second embodiment;

FIG. 10 shows a rear view of a second embodiment thereof;

FIG. 11 shows a left side view of a second embodiment thereof;

FIG. 12 shows a right side view of a second embodiment thereof;

FIG. 13 shows a top view of a second embodiment hereof;

FIG. 14 shows a bottom view of a second embodiment thereof;

FIG. 15 shows a perspective view of a second embodiment thereof; and,

FIG. 16 shows a perspective view of a second embodiment thereof, with handles down, and with the shoulder strap attached in an extended position.
